UNITED STATES PATENT OFFICE.

WILLIAM A. DROWN, OF PHILADELPHIA, PENNSYLVANIA.

DESIGN FOR THE ORNAMENTATION OF AN UMBRELLA OR PARASOL.

SPECIFICATION forming part of Design No. 14,944, dated April 8, 1884.

Application filed January 2, 1884. Term of patent 7 years.

To all whom it may concern:

Be it known that I, WILLIAM A. DROWN, a citizen of the United States, and a resident of Philadelphia, Pennsylvania, have invented 5 a new and original Design for the Ornamentation of an Umbrella or Parasol, of which the following is a specification.

My design for an umbrella or parasol is fully shown in the accompanying drawings, Figure 10 1 being a perspective view, and Fig. 2 a plan view, of the design as applied to an eight-ribbed umbrella or parasol; Fig. 3, the design as applied to one with twelve ribs, and Fig. 15 4 the design as applied to one with sixteen ribs.

The design consists of the cover having curved bands of trimming *a*, extending from a point at or near the end of one rib over the adjoining rib at a point some distance from 20 the end of the same, and thence to a point at or near the end of the next rib, the effect in 25 an eight-ribbed parasol, such as shown in Figs.

1 and 2, being to inclose an approximately-square space on the top of the parasol. In a parasol having a greater number of ribs, however, the space inclosed may be of a different shape—a hexagon, for instance, in the case of a twelve-ribbed frame, as in Fig. 3, or an octagon where the frame has sixteen ribs, as 30 in Fig. 4.

I claim—

The within-described design for the ornamentation of an umbrella or parasol, said design comprising the curved bands of trimming *a* within the limits of the cover, and inclosing 35 a polygonal space on the top of the same, as shown and described.

In testimony whereof I have signed my name to this specification in the presence of two subscribing witnesses.

WM. A. DROWN.
